United States Patent Office

Des. 176,422
Patented Dec. 20, 1955

176,422

HAND HELD VACUUM CLEANER

Alfred W. Madl, Milwaukee, Wis., assignor to John Oster
Manufacturing Company, Milwaukee, Wis., a corporation of Wisconsin

Application August 17, 1955, Serial No. 37,535

Term of patent 14 years

(Cl. D9—2)

Fig. 1.

Fig. 2.

Fig. 3.

Fig. 4.

Fig. 5.

Figure 1 is a top perspective view of a hand held vacuum cleaner showing my new design;

The dominant features of my design reside in the portions shown in full lines.

I claim:

The ornamental design for a hand held vacuum cleaner, as shown and described.
